H. DOURIF

STONE GRINDING MILL

Filed April 1, 1924

2 Sheets-Sheet 2

UNITED STATES PATENT OFFICE.

HENRI DOURIF, OF HUNTINGTON, WEST VIRGINIA.

STONE-GRINDING MILL.

Application filed April 1, 1924. Serial No. 703,495.

To all whom it may concern:

Be it known that I, HENRI DOURIF, a chemical engineer, citizen of the Republic of France, residing at Huntington, in the 5 county of Cabell and State of West Virginia, have invented certain new and useful Improvements in Stone-Grinding Mills, of which the following is a specification.

This invention relates to improvements in 10 stone grinding mills, and particularly to improvements in overdriven and underdriven wet grinding stone mills.

In the type of mill above mentioned, the 15 grinding takes place between a pair of stones under the crushing effect of the weight of the top stone, which revolves on the flat top of the stationary stone thereunder, while at the same time providing a connection with this stone for guiding and 20 driving it, which will permit the free movement of the stone, toward the stationary stone, for effecting the grinding of the particles therebetween. With this class of mills, it is usual to mount a bearing structure 25 and other supporting and guiding elements over the top of the moving stone, which occasions considerable delay, in the event that removal of either stone is necessary for the purpose of refacing the grinding 30 surfaces, as it is necessary to remove all of this structure together with the driving connections to the stones before the removal of either stone can be effected. It will be 35 at once appreciated that this consumes considerable time and labor, which delays the output of the products produced in the mill, in addition to adding considerable expense 40 in removing and replacing this structure.

The type of mill, above referred to, is 45 one which is used particularly for colloidal grinding purposes. Colloidal grinding mills of this character, which are usually called "batch mills" are used for grinding disintegrated ultramarine, in the manufacture 50 of ultramarine blue pigments. In the manufacture of these pigments it is well known in the art, that the quality of the pigments produced is the result of the fineness of the product produced in the colloidal grinding mill, and the finer the products, the higher 55 the quality of pigments. The most generally used present method of colloidal grinding for ultramarine employs a batch mill having a bearing in the bottom of the tank receiving the lower end of the drive shaft for the movable stone which extends above

the tank and is driven by suitable apparatus above the tank, and for this reason is called an overdriven mill. In view of the fact that the grinding stones of these mills weigh in 60 the neighborhood of nine hundred pounds, and as frequent redressing of the active faces of the grinding stones is necessary, it will be seen that considerable difficulty is 65 experienced and time lost in the production of pigments in the removal of the driving apparatus for permitting the removal of the stones as above set forth. In all colloidal grinding mills of this character, the movable stone has free contact with the grinding 70 face of the stationary stone, and in no case is there any means for holding the stones in spaced relation or providing any space therebetween, but on the other hand, the weight of the stone is depended upon to maintain 75 intimate contact between the faces of the movable and stationary stones, in order to effect a colloidal grinding of the disintegrated ultramarine which is supplied to the tank with substantial batches of water, so 80 that a batch of ultramarine to be ground will substantially fill the tank.

Another disadvantageous feature of the 85 type of mills now in use is in the manner of connecting the driving means with the movable stone, which at present results in considerable vibration being transmitted to the driving means and the mounting structure therefor, due to the vibration of the grinding 90 stone, in the grinding operation, and which is a very undesirable feature as it reduces the life of the driving structure.

This invention is designed in view of the 95 above noted considerations, to materially improve the constructions of colloidal batch grinding mills and to provide what may be termed an under-driven colloidal batch mill.

This invention is designed to materially 100 improve the construction of the type of mill above mentioned, and overcome the disadvantages of present structures, some of which are pointed out above, by providing a bearing structure, and mounting therefor, arranged in such a manner that the driving means or connection with the stone are 105 readily removable from the drive shaft which will immediately permit the removal of the grinding stones.

It is another object of the invention to 110 provide a special bearing structure, carried by the container, mounting the stationary grinding stone, and formed so that the mov-

but at the same time permitting the ready removal of the bearing from the column by sliding it upwardly and outwardly from the enlarged end 22. The upper end of the shaft 4 is provided with a bore 26, which extends downwardly through the shaft, and outwardly in the portion mounted in the bearing 24, so that lubricant may be supplied to the bearing.

10 The driving unit for the movable stone is indicated generally at 27, and comprises a cross head 28, formed in the central portion with an opening 29, for receiving the shaft 4, the cross head being slidable on the shaft, and held against rotation thereon by a key 30, and adapted to be secured in any set position in rigid connection with the shaft 4 by a suitable set screw 31. Limiting screws 32 mounted in the shaft 4 above the bearing 24 and the upper end of the tubular housing 18 limit the downward sliding movement of the cross head, in its application to the shaft. The outer ends of the cross head are provided with bores 33 which receive driving rods 34, which rods are slidably in the bores 33, and are adapted to be secured in adjusted position by suitable set screws 35. The upper ends of the driving rods 34, are provided with a plurality of spaced transverse openings 36, for receiving said pins 37, which are adapted to be positioned in any one of the openings 36 in the drive rods for determining the adjustment thereof in relation to the cross head 28. 25 Keys 38 prevent the rotation of the drive rod in the cross head, in an obvious manner. The movable or rotatable grinding stone 16 is provided, in the present case, with a pair of diametrically opposite recesses 39, which are of frusto-pyramidal form, and open into the central opening 17 of the stone, to permit the insertion and removal of driving blocks 40. The outer sides of the drive blocks are of frusto-pyramidal form, to provide an accurate fit with the recesses 39 in the stone, the blocks being cemented or otherwise secured in the recesses to prevent movement thereof after insertion into place. The driving blocks are formed with recesses 41, opening through the inner sides thereof, as clearly shown in Figure 5 of the drawings, and which are adapted to loosely receive the lower ends of the drive rods 34, as shown in Figure 2. A clearance is provided 40 between the lower ends of these rods and the bottom of the recess 41, in order to prevent the transmission of vibration from the driving stone in operation, to the drive unit 27 and the shaft 4, which would otherwise place an undesirable strain and wear on the driving unit and shaft, together with the mounting bearings therefor, and thereby lessen the life and efficient operation of the grinding mill.

60 The bottom portion of the container 1 is

provided with a filler of suitable material, around the stationary grinding stone 12 and in the opening 13 thereof above the flange 19 of the tubular column, as indicated at 42, for providing an inner bottom surface for 70 the container of a smooth character, slightly below the upper edge or grinding surface 15 of the stationary grinding stone. The filler also insures the watertightness of the several parts assembled at the bottom of the 75 container. This filler further secures the stationary stone against vibration on the bottom 7.

From the above description, it will be seen that this invention includes a structure 80 wherein the movable grinding stone may be readily removed from its assembled relation, in the container 1, by merely removing the driving unit 27 from the drive shaft 4, which is accomplished by loosening the set screw 85 31, following which the unit may be slidably removed from the shaft, and the movable stone 16 also removed over the enlarged end 22 of the tubular housing 18, as the opening 17 is substantially larger than the portion 90 22 of the bearing housing. Provision is also made for a convenient adjustment of the drive rod 34, so that the lower end thereof will always seat in the recesses 41 below the upper face of the rotatable stone 16, in order 95 to center the driving impulse below the upper surface of the stone, while at the same time providing a loose driving connection independent of any connection with the stone, and thereby eliminating the transmission 100 of vibration to the driving unit. It will also be understood that the bearing 24 is conveniently mounted in the enlarged upper end of the tubular housing 18, so that it may be readily removed therefrom for adjustment or renewal. The manner of assembling the bottom 7 to the tubular tub 6 and seating the stationary grinding stone 12 on the bottom, having the cooperating portions 105 for preventing rotation of the stone when seated, provides an exceedingly convenient construction which is held in assembled relation, and in water tight connection by the filler 42.

The tubular column 18 can also be economically constructed for mounting the upper bearing 24, in the manner described, and which cooperates with the driving unit, in permitting the ready removal of the grinding stone, without removing the upper bearing from the tubular housing or the housing from assembled connection with the container 1.

As heretofore stated, the above-described mill is used as a batch mill for colloidal grinding and employs the principles of the under-driven type of mill in the operation of the movable stone, in order that ready and convenient access may be had to the removable stone and the interior of the tank 130

with merely the removal of the cross head and driving rods 34, so that the stone may be removed for redressing or for other purposes. A further advantage of the construction above described is in the provision of an under driven mill of this character, of a substantially rigid bearing for the shaft, at the upper end thereof, and at the point where the power for driving the movable stone is taken off. The loose engagement of the rods 34 with the drive blocks in the movable stone prevents the vibration of the stone in grinding from being transmitted to the drive shaft, which would cause irreparable damage to the bearings and wear the parts in an exceedingly short time.

In the operation of a colloidal grinding mill of this type, the movable stone is always in contact with the active face of the stationary stone through the weight thereof in order to effect the colloidal grinding of disintegrated material placed therein. During this colloidal grinding of the material, it is found, from actual practice, that the portion of the grinding stone adjacent the center will wear considerably less than the portions adjacent the periphery of the stone, and that due to the fact that parts of the faces of these stones are harder than other parts the grinding faces will become uneven, as the parts which are softer wear away. This wearing of the outer portion in advance of the central portion requires frequent removal of the grinding stone, in order that they may be redressed to produce efficient colloidal grinding results. As the stones wear away, it frequently happens that they wear considerably more on one side than another and the redressing thereof does not always accurately replace the stones in their original relation. It results from this that frequently the stones rotate in a plane, the axis of which is slightly out of line with the shaft, and in the case of a direct driving connection with the stone, the vibrations thereof during grinding are transmitted to the shaft which destroys the bearings. In the present invention, however, the stone is free to operate freely under all conditions of unevenness and wear, and still operate efficiently, without transmitting vibrations to the drive shaft, and this results through the particular character of free connections between the drive rod and the rods 34.

In the operation of a number of these mills constructed in accordance with this invention, it has been found that the output of each mill has been considerably increased through the convenient manner of providing access for removing the grinding stones for redressing, so that the mills may be kept in more continuous operation than has heretofore been possible in the art, with the obtainance of the usual degree of efficiency required. In the provision of a batch for

grinding in the container 6, the same is filled substantially to the top of the bearing column 18 and it will be seen that no parts of the shafts or bearings are subject to the destructive action of the ultramarine or other content of the batch being ground, and at the same time sufficient operation of the stone is attained, without the transmitting of vibration to the drive shaft. A filler of Babbitt metal or the like may be placed between the ends of the sections 24 and the bottom of the guides in the bearing column for fixing the bearing in set position after the same has been inserted into the column, and which may be thereafter readily removed when desired.

A circulation of the batch within the tank is obtained in devices of this character by providing small grooves extending diagonally with respect to the diameter of the stone in one of the active faces of one of the stones, preferably the movable stone, so that in the rotation of said stone will have a tendency to force the liquid and material thereunder outwardly and draw new material inwardly through the center, so as to provide for a continuous circulation of the batch between the grinding faces of removable and stationary stones.

What is claimed is:

1. In combination in a colloidal batch grinding mill, a container having a bottom formed with an opening in the central portion, a tubular column mounted in the bottom around the opening, an annular stationary grinding stone removably seated on the bottom of the container in concentric relation to the column, cooperating means on the grinding stone and the bottom of the container for preventing rotation thereof on the bottom, an annular rotatable grinding stone mounted around the column on the stationary stone for grinding co-operation therewith, and driving means extending thru the tubular column for driving the rotatable grinding stone.
2. In an under-driven batch mill, a container having a bottom formed with an opening in the central portion, a tubular column mounted in the bottom around the opening, the bottom being provided with upwardly projected radial ribs, a stationary grinding stone adapted to seat on the bottom and having radially extending recesses for receiving the ribs, a movable grinding stone mounted on the stationary stone around the column for grinding co-operation therewith, and driving means extending through the tubular column for the movable stone.
3. In a colloidal batch grinding mill, a container, a removable bottom on said container, a stationary grinding stone seated on the bottom of said container, a filler for the container adapted to form the in-

terior bottom surface thereof, between the grinding stone and the container walls and retaining said stone in set position, a movable grinding stone for grinding cooperation with the stationary stone, and driving means for said movable stone.

4. In a colloidal batch grinding mill, a container, having a central opening in the bottom thereof provided with an upwardly projecting neck surrounding said opening, a bearing column mounted on and extending upwardly from said neck, an annular stationary grinding stone formed with a central opening adapted to fit over the bearing column and the neck and seat on the bottom of said container, means for holding said stationary stone against rotation in seated position, a filler for the bottom portion of the container adapted to seal the mountings of the stationary stone and the bearing column and form an interior bottom surface in the container, a rotatable grinding stone adapted for grinding cooperation with the stationary stone, and driving means having bearings in said column for rotating said rotatable stone.

5. In combination in a colloidal batch grinding mill, a container having a removable bottom formed with a central opening, a bearing column mounted in the container over the central opening, an annular stationary grinding stone having a central opening adapted to receive the bearing column, said stone being seated on the bottom and held against rotation thereon, means carried by the bottom for centering the bearing column and the stationary grinding stone in concentric relation, and sealing means for the bottom of the container adapted to form the inside bottom portion thereof.

6. In combination in a colloidal batch grinding mill, a container having a bottom formed with a central opening, a bearing column mounted in said container over the said central opening, a stationary grinding stone having a central opening positioned over said bearing column and seated against rotation on the bottom of said container, means carried by the bottom for centering said bearing column and grinding stone, a rotatable grinding stone having a central opening adapted to receive the bearing column for positioning in grinding cooperation with said stationary stone, and removable driving means having bearings in said column for driving said rotatable stone.

7. In combination in a colloidal grinding mill, a container formed with an opening in the central portion of the bottom thereof, a bearing column removably mounted on the bottom of said container and extending upwardly therefrom, in concentric relation with said opening, a bearing remov-

ably mounted in said column, a stationary grinding member mounted in the bottom of said container around the column, a movable grinding member cooperating therewith, and mounted around the column and a driving means extending through the bearing in the column for driving said movable grinding member.

8. A grinding mill of the class described including a container having the bottom formed with a central opening, a tubular bearing column removably mounted in the bottom of said container around said opening, a bearing slidably and removably mounted in the upper end of said bearing column, a drive shaft extending through the opening in the bottom of said container and said bearing column and received by said bearing, a stationary grinding member mounted in said container, a movable grinding member mounted in said container for cooperation with the stationary member, and driving means between said shaft and movable driving member, for driving the movable member to effect a grinding cooperation thereof, said driving means being positioned above the movable member.

9. An underdriven colloidal batch grinding mill comprising a container formed with a central opening in the bottom thereof, a column mounted in the bottom of said container and around the opening, a drive shaft extending through said container bottom and said column, a stationary grinding member mounted in said container, a rotatable grinding member mounted in said container for grinding cooperation with said stationary member, and a driving unit removably mounted on said shaft and having driving cooperation with the rotatable grinding member for effecting the operation thereof in the rotation of said shaft.

10. In an underdriven batch grinding mill, a container formed with a central opening in the bottom thereof, a bearing column mounted in said container around the central opening, a drive shaft extending through said column and having bearing therein, a stationary grinding member mounted in said container, a rotatable grinding member mounted in said container for grinding cooperation with said stationary member, said grinding members being mounted around said column, and a driving unit removably mounted on said shaft and having an adjustable driving connection with said rotatable grinding member for effecting the operation thereof in the rotation of the drive shaft.

11. In an underdriven batch grinding mill, a container formed with a central opening in the bottom thereof, a bearing column mounted in the container around the central opening in the bottom, a drive shaft extending through said opening and bear-

ing column and having bearing therein, a stationary grinding member, a rotatable grinding member for cooperation with the stationary member, and a driving unit 5 movably mounted on said shaft above said column having a free driving engagement with said rotatable driving member.

12. In an underdriven batch grinding mill, a container formed with a central 10 opening in the bottom thereof, a bearing column mounted in the container around the central opening in the bottom, a drive shaft extending through said opening and bearing column and having bearing therein, 15 a stationary grinding member, a rotatable grinding member for cooperation with the stationary member, and a driving unit including a cross head removably mounted on said driving shaft, and drive rods ad- 20 justably mounted in said head and having a free driving engagement with said rotatable grinding member, for effecting the rotation thereof, in the operation of the shaft.

13. In a colloidal batch grinding mill, a 25 container, a drive shaft rotatably mounted in said container, a stationary grinding member mounted in the container, a rotatable grinding member mounted in said container for grinding cooperation with said 30 stationary member, said rotatable grinding member being formed with a plurality of recesses, driving blocks mounted in said recesses, and driving means removably mounted on said drive shaft above said grinding mem- 35 bers, and having a loose engagement with said drive blocks for effecting an operation of the rotatable grinding member in the rotation of the shaft, and centering the driving impulse below the surface of said rotatable 40 driving member.

14. In combination in a batch grinding mill, a container, a shaft rotatably mounted in said container, a stationary grinding member mounted in said container, a rotatable grinding member mounted in said container for grinding cooperation with said container for grinding cooperation with said stationary member, said rotatable grinding member being formed with a plurality of frusto-pyramidal shaped recesses, 50 drive blocks of frusto-pyramidal form mounted in the recesses in said rotatable grinding member, and driving means carried by said drive shaft beyond the grinding members, having a loose driving engagement in said drive blocks.

15. In combination in an underdriven batch mill, a container, having a central opening in the bottom thereof, a bearing column mounted in said container and surrounding the central opening in the bottom thereof, a drive shaft rotatably mounted and having bearings in said column, an annular stationary grinding member hav- 60 ing a central opening adapted to receive

said column and mounted in concentric relation thereto, in the bottom of said container, a rotatable grinding member having a central opening adapted to receive said column positioned on the stationary grinding member for grinding cooperation therewith, and a removable drive unit mounted on said drive shaft beyond the rotatable grinding member and having a loose driving engagement with said rotatable grinding 75 member, the center of the driving impulse with the rotatable grinding member being below the surface of said grinding member, whereby the grinding member may be removed from said container, following the removal of the driving unit from said shaft.

16. An underdriven batch grinding mill of the class described, wherein a container is provided with a central opening in the bottom thereof receiving the drive shaft for the mill, a bearing column comprising an elongated tubular member mounted on the bottom of said container, in registry with the central opening, the upper end of said member being formed with a bearing housing and extending upwardly in said container to the top portion thereof, said bearing housing removably receiving a bearing for the drive shaft.

17. A batch grinding mill comprising a container having a central opening in the bottom, a tubular column mounted on the bottom of the container over the opening and terminating adjacent the top portion of said container, a ring shaped stationary grinding stone mounted on the bottom of the container in concentric relation with the column, a rotatable ring shaped grinding stone mounted in the container on the stationary grinding stone, said column terminating substantially above the top of the rotatable stone, a drive shaft extending through and terminating above the column, and a driving unit removably mounted on the shaft above the column having a free driving connection with the rotatable stone.

18. An underdriven batch grinding mill comprising a container having a bottom plate adapted for mounting on a supporting structure, a tub removably mounted on the bottom plate, a tubular bearing column mounted in the central portion of the bottom plate, and having the central portion thereof registering with an opening in the bottom plate, a stationary grinding stone mounted on the bottom plate around the column, a rotatable grinding stone mounted around the column on the stationary grinding stone, said bearing column extending above the grinding stone, and driving means having a bearing in the upper end of the bearing column and extending above the grinding stone and having a free driving connection with the rotatable stone.

19. An underdriven batch grinding mill

comprising a bottom plate having a central opening, a tub mounted on said plate, forming a batch container therewith, a bearing column rigidly mounted on the bottom plate, a stationary grinding stone positioned on the bottom plate, and sealed means for securing said elements in set relation providing a liquid tight container.

20. An underdriven batch grinding mill, wherein a batch container is provided with a central opening in the bottom, and a tubular bearing column extending upwardly from said bottom in registry with said opening, and wherein the container removably receives stationary and removable grinding stones positioned around said column, and wherein the column forms a means for protecting a drive shaft extending therethrough, and having bearings in the upper end; a drive unit for the movable grinding stone removably mounted on said shaft beyond said column, having adjustable drive means extending into the container for free driving engagement with said movable stone.

21. An underdriven batch grinding mill, wherein a batch container is provided with a central opening in the bottom, and a tubular bearing column extending upwardly from said bottom in registry with said

opening, and wherein the container removably receives stationary and removable grinding stones positioned around said column, and wherein the column forms a means for protecting a drive shaft extending therethrough and having bearings in the upper end; a drive unit for the movable grinding stone removably mounted on the shaft beyond said column having driving extensions adjustably carried thereby projecting into engagement with said movable grinding stone, the extensions and the grinding stone having free engagement permitting limited relative movement in all directions of said grinding stone.

22. An underdriven batch grinding mill, wherein a batch container is formed with a central opening in the bottom, a bearing column formed of a tubular member flanged at the lower end to seat on said container bottom, means securing said column in rigid position on said bottom in registry with the opening therein, and a bearing housing formed in the upper end of said member for receiving a bearing for a drive shaft extending therethrough.

In testimony whereof I affix my signature.

HENRI DOURIF.
